UNITED STATES PATENT OFFICE.

WILLIAM CORDWELL AND DYSON BARKER, OF MANCHESTER, ENGLAND.

COTTON-COMBING MACHINE.

Application filed June 4, 1920. Serial No. 386,510.

To all whom it may concern:

Be it known that we, WILLIAM CORDWELL and DYSON BARKER, subjects of the King of Great Britain and Ireland, and residents 5 of Manchester, in the county of Lancaster, England, have invented certain Improvements in Cotton-Combing Machines, of which the following is a specification.

This invention relates to improvements in 10 machines for combing cotton and whilst it has particular reference to what is known as the "Nasmith" machine is nevertheless applicable to combing machines of other types, the object being to provide improved means 15 for driving the detaching roller so as to accomplish the backward and forward movements of the latter in a more efficient manner.

Our invention will be fully described with 20 reference to the accompanying drawing in which

Fig. 1 is an end elevation of a device constructed in accordance with our invention.

25 Fig. 2 is a plan view of the same. Fig. 3 is a detail front view and Fig. 4 a plan view of the section wheels or toothed segments *g* and *h*, showing also the wheels *e*, *f* and *i* in dotted lines, and drawn to a 30 larger scale.

With the aforesaid objects in view our invention consists in mounting upon two studs *a* and *b* arranged at a little distance apart from each other and secured to the 35 machine frame *c* two wheels *e* and *f* of a definite number of teeth say for instance, 20, in gear with each other, the same wheels being compounded with section or spaced wheels *g* and *h*, that is to say wheels having only a few teeth say 7 and 3, respectively and the rest of their peripheries blank. These section wheels *g* and *h* are adapted to gear at the required times with another wheel *i* mounted upon a stud *j* 40 above the studs *a* and *b* this third wheel having a definite number of teeth say 15. The section wheel or toothed segment *g* has a toothless or blank portion *g*¹, and the section wheel or toothed segment *h* has a blank portion *h*¹. The spaced wheels *g* and *h* are driven continuously through the agency of the fully toothed wheels *e*, *f*, with which they are compounded, by another wheel *k* driven in any suitable manner from a 45 convenient source, the arrangement being such

that the section or spaced wheels *g* and *h* come alternately into and out of gear with the wheel *i* above them so as at one time to turn said wheel a definite distance clockwise and at another time a definite distance anti-clockwise and also allow such wheel to dwell between its movements, all in accordance with the known movements of the detaching roller of the combing machine. The aforesaid arrangement of gears is generally 60 sufficient for accomplishing the objects in view but as there are times when both gears *g* and *h* are out of mesh with the wheel *i* it is advisable to provide means for locking or holding such gear stationary during the 65 dwelling periods of the detaching roller to ensure the various gears coming into mesh properly at the same point each time, so as not to disturb the sequence of known operations of the detaching roller. To this 70 end we employ in connection with and fixed to the third wheel *i* a star-shaped wheel *m* cut away on its periphery at four different points *n*. This star wheel co-acts with discs or cams *o* and *p* fixed to or formed 75 in one with the section wheels *g* and *h*. Each of the cams has its edge stepped down at *q* to enable the points *r* of the star wheel to pass when it and the gear wheel *i* are rotating. On the other hand the edge of each 80 cam is formed with a portion *s* adjacent to the step *q* concentric to the centre of its supporting stud, such parts *s* in each case engaging the star wheel in or about the manner shown at the right hand side of 85 Fig. 1, so as to hold said wheel from rotating during the passage of the concentric part of the cam and whilst the section teeth of the spaced wheels are out of gear with wheel *i*. 90

The section wheels *g* and *h* are continuously driven at a constant rate of speed but the wheel *i* driven by them and likewise the star wheel *m* are first driven in one direction, remain stationary and are 100 then driven in the opposite direction, the stationary periods coinciding with the stationary periods of the detaching roller of the combing machine. Motion is communicated to the detaching roller (not shown in 105 the drawing) by a pinion *t*, in gear with wheel *i*, fixed on shaft *u* which has also fixed upon it a wheel *v* gearing with a pinion *w* on the shaft *x* of the detaching roller. 110

What we claim as our invention and desire to protect by Letters Patent is:—

1. A driving mechanism adapted to operate the detaching roller of a combing machine, comprising two toothed driving wheels, intermeshing with each other, two toothed segments revolving with the respective driving wheels, a toothed driven wheel arranged in the same plane with the 10 said toothed segments and revolved by them intermittently first in one direction and then in the other direction, a star wheel revolving with the said driven wheel, and two cams revolving with the respective 15 toothed segments and operating to lock the star wheel and driven wheel when the toothed segments are out of driving engagement with the said driven wheel.

2. In a fibre-combing machine the means 20 for controlling the detaching roller com-

prising driven wheels intermeshing with each other, section wheels compounded with the driven wheels, a wheel adapted to be driven intermittently in opposite directions by the section wheels, a star wheel 25 fixed to the intermittently-driven wheel and cams fixed to the section wheels to lock the star wheel in position when the section wheels are out of gear with the intermittently-driven wheel and allow the latter 30 and star wheel to rotate when the gears engage.

In testimony whereof we have hereunto set our hands in the presence of two witnesses.

WILLIAM CORDWELL
DYSON BARKER.
